UNITED STATES PATENT OFFICE.

FRANK F. LANDIS, OF WAYNESBORO, PENNSYLVANIA.

SELF-OILING JOURNAL-BEARING.

No. 927,361.

Specification of Letters Patent.

Patented July 6, 1909.

Application filed August 20, 1904, Serial No. 221,491. Renewed December 11, 1908. Serial No. 467,079.

To all whom it may concern:

Be it known that I, FRANK F. LANDIS, a citizen of the United States, residing at Waynesboro, in the county of Franklin and

5 State of Pennsylvania, have invented certain new and useful Improvements in Self-Oiling Journal-Bearings, of which the following is a specification.

10 My said invention consists in an improved construction of self-oiling journal bearings, whereby a bearing of such character is provided which will be certain in its operation under all conditions, all as will be hereinafter more fully described and claimed.

15 Referring to the accompanying drawings which are made a part hereof and on which similar reference letters indicate similar parts, Figure 1 is a view of one of my improved journal bearings partly in elevation, 20 and partly in central longitudinal section, Fig. 2 a transverse section looking in the direction indicated by the arrows from the dotted line 2-2 in Fig. 1, Fig. 3 a cross section looking in the direction indicated by 25 the arrows from the dotted line 3-3 in Fig. 1 omitting the parts B and B², and, Fig. 4 an end elevation.

In said drawings, the portions marked A represent the main shell of the bearing, B 30 a yoke and binder in which said shell is mounted, and C a ring carrying the oiling device. The shell A is substantially of a well known form containing a bearing A⁴ for the journal or shaft, which bearing is cast in 35 piece with said shell and with a central opening A¹ which divides the bearing proper into two parts, which are joined by the oil-chamber A² cast on the lower side of said shell A, which is thus a one-piece casting.

40 The central portion a of the shell is enlarged to form a ring surrounding the center of the shell and said ring is turned to semi-spherical form on its outside surface. Both parts of the bearing A⁴ are lined with Bab- 45 bitt-metal or other suitable metal A³, and a groove a¹ is formed in the upper side of said bearings extending longitudinally thereof from the inner ends of the two parts nearly to their outer ends. A circumferential 50 groove a² is also formed near the ends of the bearings and a perforation a³ leads from the lower side thereof into the oil chamber A².

55 A tube or perforation A⁵ is formed on one side of the shell leading into the oil chamber through which the oil is supplied thereto. Said tube is closed by a cap a⁴.

A screw-threaded opening a⁵, closed by a screw plug a⁶, is formed in the lower side of the oil chamber through which it may be cleaned. 60

The yoke and binder B is formed to fit snugly around the enlarged central ring or portion a of the shell and is connected therewith by a screw B¹ which extends through a screw-threaded perforation in the lower side of said yoke, its point being formed conical and engaging a shallow perforation in the under side of said shell, as shown. By this means any longitudinal or rotary movement of said shell is prevented while it 70 is permitted to adjust itself to any variation in the alinement of the journal. The top of said yoke is preferably formed open and connected by a cap piece B² secured thereto by bolts or set-screws b. Said cap also covers the opening in the top of the enlarged portion of the shell. A leather or other suitable gasket b¹ is interposed between the edges of said shell and said cap for the purpose of making the joints between them oil-tight. 75

The ring C is split upon one side and has a transverse bolt c extending through ears formed at each side of the slit therein, by which the two parts may be drawn together, 85 and the ring clamped to the shaft or journal. An arm of paddle c¹ is inserted in the slit in said ring and held by means of said bolts, or carried in any preferred manner. Said arm is of the form shown in Fig. 1, being adapted to extend into the oil-chamber nearly to the bottom and enter the body of lubricant therein and carry the same around, and by centrifugal force throw said lubricant into the open space between the 95 ends of the bearings A⁴ and flood said space as the shaft or journal revolves, the lubricant running into the longitudinal groove a¹ along the top of the bearings and keeping said bearings thoroughly lubricated. 100

In assembling the parts, the ring C is placed in the central opening in the bearing before cap B² is put in place, and said bearing then slid upon the shaft or journaled to the position desired. When in said position the screw c is tightened to securely clamp said ring C, with its projecting arm c¹, upon said shaft or journal. The cap B² with the gasket b¹ is then put into place. The ring C rotates with the shaft and through the arm c¹ operates to carry the lubricant by centrifugal force into the upper part of the central 110

chamber, from which it passes through the grooves a^1 along the surface of the journal and thus keeps the bearings thoroughly lubricated. A principal object of said ring 5 C and the wide end bearings A^3 is to prevent any longitudinal movement of said journal or shaft. It being firmly clamped to the shaft its sides will abut against the inner adjacent wide ends A^3 of said bearings and 10 thus secure this result. The Babbitt-metal lining is widened at this part to cover the ends of bearing parts A^4 and provide a wide bearing surface A^3 for the sides of said ring C. By this arrangement an oiler is provided 15 which will not become inoperative by reason of the congealing of the oil or lubricant in the oil chamber as the arm c^1 attached to ring C is held positively to the shaft and must revolve therewith and keep said lubricant agitated. 20

Having thus fully described my said invention what I claim as new and desire to secure by Letters Patent is—

1. A self-oiling journal bearing comprising a casing having the bearings therein, and formed with a central opening which divides said bearings, a yoke for supporting said casing, a conical pin engaging a conical recess forming the engagement between the 25 two parts, a removable cap for the opening in said casing which also serves to connect the ends of the yoke, and oil distributing means mounted upon the shaft between the two parts of the bearing, substantially as 30 set forth.

2. A self-oiling journal bearing comprising a casing, bearings formed in said casing, said casing being formed with an opening that divides said bearings, and its central 35 portion on the under side being formed with a semi-spherical contour, a yoke provided with a conical pointed screw for supporting said casing, the point of said screw being adapted to engage with a suitable recess in 40 the central portion of said casing, the journal, the oil distributing means carried thereby, and the cover for said opening in said casing also adapted to connect the ends of the yoke, substantially as set forth.

50 3. In a journal bearing, the combination of the shell having an enlarged central portion, a yoke or binder with an open side supporting said shell, said shell being formed with a recess, a cap for closing said recess 55 and connecting the sides of said yoke or binder, a divided bearing formed in said

shell, a ring rigidly secured to the journal between the bearing parts, and an arm projecting from said ring, substantially as set forth.

60

4. In a self-oiling journal bearing, the combination of the shell formed with an oil chamber in its lower side, a journal bearing in each end of said shell, there being an opening in the top of said shell into the 65 space between said journal bearings, a yoke for supporting said shell provided with a removable cap adapted to close said opening, the shaft or journal mounted in said bearings, a ring rigidly secured thereon between 70 said bearings, and a projection on said ring, substantially as set forth.

5. In a self-oiling journal bearing, the combination, of the shell formed with a central portion of enlarged diameter and an 75 opening leading through the top of said enlarged portion of said shell, a journal bearing in each end of said shell, a yoke engaging with the underside of said shell and a removable cap adapted to close said opening 80 and to connect the sides of the yoke, all substantially as set forth.

6. In a self-oiling journal bearing, the combination of the shell formed with an opening in its top and having a bearing in 85 each end, a yoke supporting said shell at its center, a removable cap adapted to close the opening in said shell, there being a longitudinal groove formed in the top of each bearing and a circumferential groove near 90 their ends with a perforation leading therefrom into the oil chamber, substantially as set forth.

7. In a self-oiling journal bearing, the combination of the body cast in one piece 95 with a bearing, which bearing is divided by an annular opening, said body being in piece with both ends of said bearing, the journal or shaft mounted therein, and a ring secured to said journal in said opening, the sides of 100 which provide end thrust bearings to prevent lateral movement of said journal, said ring having a projection, for the purpose set forth.

In witness whereof, I have hereunto set 105 my hand and seal at Washington, D. C., this twenty-fifth day of July, A. D. nineteen hundred and four.

FRANK F. LANDIS. [L.S.]
